UNITED STATES PATENT OFFICE.

BENJAMIN J. COHON, OF WESTWOOD, NEW JERSEY, AND LOUIS MOSKOWITZ, OF BROOKLYN, NEW YORK.

LOCK.

Application filed November 6, 1920. Serial No. 422,133.

To all whom it may concern:

Be it known that we, BENJAMIN J. COHON and LOUIS MOSKOWITZ, citizens of the United States, and residing in Westwood, in the county of Bergen and State of New Jersey, and Brooklyn, in the county of Kings and State of New York, respectively, have invented certain new and useful Improvements in Locks, of which the following is a specification.

Our invention relates to an improved lock; particularly a lock comprising a bolt and parts for enabling the bolt to be moved into and out of engaging position with respect to a strike-plate cooperating with same.

An object of this invention is to provide a lock having a compound bolt consisting of a plurality of members, each of which receives bodily movement when the lock is to be actuated; the bolt thus constituting a double-latch bolt which can have positive engagement with the strike-plate at more than one point, and thus render the lock incapable of being opened except by proper manipulation of the parts in the contemplated and regular way.

Another object of our invention is to provide a lock of strong but simple construction, inexpensive to manufacture, and easy to mount and operate when attached to a door, window or the like of a room or other enclosure.

The above and other objects and advantages of our invention are fully set forth in the following specification, taken with the accompanying drawings; and the novel features of our lock are precisely defined in the appended claims. But this disclosure is explanatory only, and the principle of our invention may be embodied in other constructions that are similar in effect, as indicated by differences in the modes by which the characteristics of our improvement, as stated in the several claims, are expressed.

On the drawings:

Figure 1 is a side view showing the mechanism of our improved lock with the bolt retracted;

Figure 2 is a similar view showing the mechanism of our lock with the bolt projected;

Figure 3 is a horizontal section on the line 3—3 in Figure 2;

Figures 4 and 5 are similar respectively to

Figures 1 and 2 but show the mechanism of our lock from the opposite side;

Figure 6 is a vertical section on the line 6—6 in Figure 5;

Figure 7 presents an inside view of the casing for our lock;

Figures 8 and 10 show in side elevation the members constituting the bolt of our lock;

Figure 9 is a similar view of a carrier for the bolt; and

Figures 11, 12 and 13 illustrate cams for operating the parts shown in Figures 8, 9 and 10 respectively.

The same numerals identify the same parts throughout.

In the detailed description of what is illustrated on the drawings, we employ the numeral 1 to indicate a casing having a back 2; a removable front 3, forming a closure for the casing; a top and a bottom; and sides 4; one of which has an opening 5. Through this opening is shot the bolt 6 of the lock, this bolt comprising a pair of members 7 and 8 disposed in the casing 1. The member 7 has a lateral projection 9 at its extremity which is to be moved in and out through the opening 5; and the member 8 has a similar lateral projection 10. We arrange the members so that the projection on one extends in the opposite direction with respect to the projection on the other; the two projections constituting hooks to enable the bolt to be passed through an opening in a strike-plate and then engage the upper and lower edges thereof to secure the door or other member to which the lock is affixed in closed position. This strike-plate is not shown in the drawings. As will be understood, it is mounted on the frame or jamb of the door, etc., in such position that the opening therein will be in line with the opening 5, so that, when the lock is manipulated as required, the ends of the members 7 and 8 bearing the projections 9 and 10 can be shot out of the casing 1 through the strike-plate, or withdrawn from the strike-plate and moved back into the casing. Each of these members 7 and 8 is engaged by a carrier 11 in the casing; and when this carrier is operated to be moved towards or from the opening 5, the two members or parts 7 and 8 of the bolt 6 are caused to be moved with it.

The carrier 11 is preferably formed like

a flat plate. It lies entirely within the casing; never projecting therefrom; and its height is such that it spans the entire width of the casing inside of the latter between the 5 top 12 and bottom 13. On the other hand, its length is less than the distance between the opposite sides of the casing; hence longitudinal movement of the carrier in the casing can be effected. At its forward and 10 rear edges this carrier has transverse ribs 14, these ribs being on both sides or faces of the plate, and fitting between corresponding ribs at the front and back of the members of the bolt 6. To provide these ribs on the bolt, 15 each of the members 7 and 8 is made relatively thick at its front end, adjacent the lateral projection or hook thereon, and thus shoulders 15 are presented on both faces of the members 7 and 8, near the forward extremities thereof; while at the opposite extremities the edges of the members are bent over to provide transverse rear ribs 16. The carrier is located between the members 7 and 8 in the casing 1, and by placing the ribs 14 20 of the carrier between a shoulder 15 and the rear rib 16 of each member of the bolt, the carrier and the bolt are arranged in proper engagement, with the carrier and bolt capable of moving together towards and from 25 the side 4 having the opening 5, and the members 7 and 8 are further capable of bodily or translational movement with respect to the carrier to impel the projections 30 9 and 10 away from each other after these 35 projections have been shot out through the opening 5 and the opening in the strike-plate above-mentioned. To produce this combination of movements, the carrier 11 has a central aperture 17, and the members 7 and 8 40 each have an aperture 18 and 19 respectively; and in the aperture 17 is a cam 20, in the aperture 18 a cam 21 for the member 7, and in the aperture 19 a cam 22 for the member 8. These three cams are mounted upon a 45 shaft 23, in a bearing carried by the back 2 of the casing 1.

By virtue of these cams, the carrier and the members 7 and 8 can all move together in one direction towards and from the opening 5. When the members have been moved towards this opening till the projections 9 and 10 have travelled out of the casing as far as they will go, the members 7 and 8 can be given bodily or translational movement, 55 with respect to the carrier, in a direction transverse to the direction just referred to, to impel the lateral projections 9 and 10 away from each other, so that they can engage with the opposite edges of the opening in the strike-plate; and the door is then secured. To undo the lock, the members 7 and 60 8 are moved transversely of the direction of motion of the carrier in such a way as to impel the projections 9 and 10 towards each other; and then carrier and bolt to-

gether are moved back into the casing, away from the opening 5, till the projections or hooks 9 and 10 are completely withdrawn and the door is released.

The apertures 18 and 19 are elongated, 70 and have preferably the shape shown in Figures 8 and 10, the greatest dimension of these apertures being in the direction in which the carrier 11 can move. As for the aperture 17, it is elongated somewhat across the line of movement of the carrier, and has substantially the shape of a true heart, with a reentrant projection 24 on its forward edge and a similar projection 25 on its rear edge, and a recess 26 in the lower end of the aperture 17, between these two projections. The cam 20 in this aperture is provided with a nose 27 at its forward corner; the rear corner being indicated at 28, and the circumferential portion of the cam curved substantially 85 on the arc of a circle, as indicated at 29. We give to the cams 18 and 19 substantially the shape of a triangle, with rounded advance corners 30, rounded rear corners 31, and circularly curved outer edges 32. These two 90 cams 18 and 19 are spaced apart a distance of about 180 angular degrees, to afford the mode of operation desired.

The method by which the lock is operated may now be described in full. When the 95 bolt is withdrawn, the parts all occupy the positions shown in Figures 1 and 4: the carrier lying in the casing remote from the opening 5, and the front edges of the projections 9 and 10 being flush with this opening; with the rear corner 28 of the cam 20 100 against the rear edge of the aperture 17. The first rotation of the shaft 23 causes the nose 27 to strike against the projection 24, and the carrier 11 is consequently moved 105 in unison with the members 7 and 8 to make the projections 9 and 10 pass through the opening 5 and the hole in the strike-plate to reach operative position. At this time the member 7, which lies adjacent the back 2, is 110 in its lowermost position; and the member 8, which is adjacent the front 3, is in its uppermost position; and these positions of the two members are maintained for about 115 90 angular degrees of rotation of the cam 20. That is, the shaft 23 and cam 20 thereon will turn through a quarter of a circle and the only movement effected will be movement of the carrier and both parts of the bolt in unison towards the side of the 120 casing containing the opening 5: without the members 7 and 8 changing their relative positions at all; because the circular edge 32 of the cam 21 in the aperture 18 of the member 7 will be engaging the lower edge of 125 the aperture 18, and the circular edge 32 of the cam 22 will be engaging the upper edge of the opening 22 of the member 8. Afterward, in the further rotation of the shaft 23, the nose 27 passes the projection 24, and 130

moves along the portion of the edge of the opening 17 in the carrier without making the carrier move any farther, till the nose 27 finally comes to rest in the recess 26. 5 During this portion of the revolution of the shaft 23, the forward corner of the cam 21 in the aperture 18 of the member 7 will engage with the upper edge of the aperture 18 and the forward corner of the cam 22 in the 10 aperture 19 of the part 8 will engage with the lower edge of the aperture 19; and the members 7 and 8 will thus be operated to move in opposite directions, transverse to the line of movement of the carrier; and the 15 two projections 9 and 10 will be impelled away from each other. Under the conditions described, the member 7 may move upward and the other member downward, although the relative movements of the two 20 members may be reversed without essential alteration of the construction we have adopted.

Therefore, when the nose 27 of the cam 20 finally stops in the recess at the lower end 25 of the opening 17 in the carrier, the cams 21 and 22 will have moved the members 7 and 8 transversely of the carrier as far as the opening 5 will allow; and the two projections 9 and 10 now have positive engagement 30 with the upper and lower edges of the strike-plate cooperating with the lock; and upon reverse movement of the shaft, the two cams 21 and 22 first move the members 7 and 8 to bring the projections 9 and 10 into 35 position to clear the aperture in the strike-plate and the opening 5; and then the rear corner of the cam 20 strikes the rear edge of the opening 17, and thus the corner 28 of the cam 20 will withdraw both carrier 40 and bolt into the casing to their positions at starting.

One will observe that, when the carrier and bolt have completed their outward movements, the cam 20 lies in such position 45 that any force on the outer ends of the members 7 and 8 tending to move them back into the casing will only exert a turning movement on the cam 20 to force the nose 27 farther into the recess 26. This result is due to the fact that the center of the edge 29 if the cam 29 lies below the level of 50 the axis of the shaft 23 and the line of movement of the carrier 11. Also, both cams 21 and 22 are revolved far enough to carry their forward corners 30 as far as or even a little 55 beyond a vertical line through the axis of the shaft. Therefore any outside force exerted against the members 7 and 8 to force the projections 9 and 10 towards each other, 60 into position to withdraw from the strike-plate and into the casing 1 can have no effect upon the bolt. The lock is thus entirely burglar-proof; for the bolt cannot be returned 65 into the casing or the lock undone except by reverse movement of the shaft and

the cams, even if one should attempt to put a tool under the lower edge of the door and lift it. In such a case, the door would not lift, because the members 7 and 8 hold it effectually against vertical movement 70 through the one member making contact with the upper edge of the aperture in the strike plate, and the other member making contact with the lower edge of said aperture.

The shaft 23 projects through the bearing therefor in the back 2, and carries a knob 33 to enable it to be operated. This knob, when the casing is mounted on the door, will be on the face of the door presented to the interior of the enclosure to which the door 80 belongs, because the lock will be affixed to that face. Inside the casing this shaft will have flats 34 to make the cams turn with the shaft, and the cam 21 adjacent the back 2 will have a stud or pin 35 to cooperate 85 with an arm 36. This arm will be inside the casing, and will be mounted to revolve, as by affixing it to the inner end of the barrel of a tumbler lock, or the inside member of a lock of any other construction. No 90 such lock is shown, because it is not a part of our invention; but it may be mounted in the door, so that the carrier and bolt can be actuated from the outside of the enclosure by means of a key. When the proper 95 key is employed, the arm 36 can be turned till it hits the pin 35, and then the bolt can be shot out into the striker-plate, or withdrawn into the casing 1 as may be desired.

We also use in the casing 1 a guide plate 100 37, which lies against the back 2. This plate has projections at its corners to engage the bottom and top of the casing, as shown at 38, to make the plate fit the casing snugly; and its upper and lower edges are 105 turned over to make guide ribs or flanges 39, with which the member 7 makes contact as it moves in the casing 1. The other member is engaged by a retainer 40, fitted to the adjacent end of the shaft inside the casing, and having an opening through which the pin 35 projects. On the outside of the shaft 23 is a groove 41 and a clip 42 in this groove holds the retainer 40 in place against the member 7.

The lock can very easily be manufactured, because all the parts can readily be produced by stamping or otherwise. It can be turned out at low cost, and mounted on any door at very little expense. Further, it is 120 adapted for a door opening either way, because no change need be made to enable it to be affixed to a door that is hung to open to the right, instead of a door that is to open to the left, for example. In any such 125 case, one need only revolve the casing 1 in a vertical plane to carry the opening 5 from right to left, or vice versa.

Having described our invention, what we believe to be new and desire to secure and 130

protect by Letters Patent of the United States is:—

1. A lock comprising a double-latch bolt consisting of a pair of members, a carrier 5 to engage each of said members, and elements to actuate the carrier and the bolt in unison and then to impart bodily movement to said members with respect to the carrier while the carrier remains stationary.
10 2. A lock comprising a double-latch bolt consisting of a pair of members, a carrier to engage said members, and elements to move the carrier and the bolt in unison, and then to impart bodily movement to said 15 members relative to the carrier to impel them in opposite directions.
3. A lock comprising a double-latch bolt consisting of a pair of independently movable members, a carrier to engage both of 20 said members, an element to move the carrier and said members in one direction, and elements to impart translational movement, with respect to the carrier, to each of said 25 members in opposite directions away from each other, and transversely to the first-named direction.
4. A lock comprising a double-latch bolt consisting of a pair of members, a carrier between said members and engaging each, 30 an element to move the carrier and said members together in one direction, and elements to impart translational movement with respect to the carrier to each of said

members in opposite directions, away from each other, and transverse to the first-named 35 direction.

5. A lock comprising a double-latch bolt consisting of a pair of independently movable members, a carrier to engage said members, one of said members having a lateral 40 projection at its extremity extending in one direction, and the other member having a lateral projection at its extremity extending in the opposite direction, and elements 45 to actuate the carrier and said members in unison and the members translationally with respect to the carrier to move said projections away from each other.

6. A lock comprising a double-latch bolt consisting of a pair of members, one of said 50 members having a lateral projection at its extremity extending in one direction, the other member having a lateral projection at its extremity extending in the opposite direction, a carrier to engage each of said 55 members, a cam to actuate the carrier to move the carrier and said members in unison, and cams to operate each of said members to give same translational movement with respect to the carrier to impel said 60 projections away from each other.

In testimony whereof, we have signed our names to this specification.

BENJAMIN J. COHON.
LOUIS MOSKOWITZ.
